Inventor:

Thomas C. Fahnestock

UNITED STATES PATENT OFFICE.

THOMAS C. FAHNESTOCK, OF CINCINNATI, OHIO.

IMPROVEMENT IN PAPER-FILES.

Specification forming part of Letters Patent No. 104,002, dated June 7, 1870.

To all whom it may concern:

Be it known that I, THOMAS C. FAHNESTOCK, of Cincinnati, in the State of Ohio, have invented certain Improvements in a Clip and File for filing and binding letters, bills, invoices, &c., with ease and dispatch, of which the following is a specification:

The nature of my invention consists in the arrangements of the parts so as to produce a direct parallel action on the press-plate that holds the paper, without the use of a lever, and in providing a means to hold the press-plate when the points are uncovered for inserting the papers to be filed, which plate, when disengaged, instantly forces the papers down or back, and holds them firmly and equally.

The accompanying drawings clearly show the construction and operation, in which Figure 1 is a perspective view of the clip and file hanging on a hook, with papers held between the back plate and moving press-plate; Fig. 2, the same, seen on top, with the spring-chambers uncovered, in order to show the coiled spring and central bolt on each side. Fig. 3 illustrates the same with the key and press-plate drawn out, the casing-prop C embracing the stem B of the key, to which it is hinged by a pivot. The press-plate D is drawn under the top or gage flange H against the front plate E, (inside,) to uncover the pins or paper points P when adding or filing papers on the same, the upper edges of which are pushed against the flange H, which gages them all to an uniform distance, and secures regularity in filing.

The back vertical portion A can be variously shaped and used as it is, or secured to a back of binders' boards or other material, and is provided on each side with a spring-chamber, J, containing a headed bolt, L, countersunk or riveted to the head or back plate A, and provided with a screw end extending through the chamber and outer cap-plate J, where it is secured by a nut, N. A spiral spring, K, is placed around the bolt in each chamber. Against the inner or lower end of said spring the prolonged and perforated ends of the press-plate D, which embrace the bolts, are brought, said press-plate being also perforated to allow the paper-holders or points P to pass through, and thus enable it to lie

against the back A by the pressure of the springs against it. In order to operate it on its bearings, which serve also as guides, the two spring-chambers J are connected about their middle, as shown, by a cross-plate, E, bent inward above at a right angle, forming a gage-flange, H, for the purpose already referred to. This cross-plate has, centrally, on its vertical face E, a square opening or bearing for the shaft or key stem B, the inner end of which is firmly attached centrally to the press-plate D. A three-sided or open case, C, with lugs on its two opposite sides, is perforated for a pivot, by which it is hinged to the outer end of the stem B of the drawing-key. This case C has also a raised flange, by which it is more easily moved by the finger or thumb.

The operation is very simple. By drawing out the key the press-plate is also drawn out against the coiled springs in the chambers, which are necessarily brought in close contact, as shown in Fig. 3; but a slight pressure on the inclined case or hinged prop C will bring it up to embrace the stem B, and consequently hold the parts in that position. When the papers are filed, as before mentioned, a touch on the flange will push the lower end of the casing-prop C out to its former inclined position, as seen in Fig. 2. The spring, acting on both ends of the press-plate D, forces the papers now under it on the points of the pins P down or back into close contact with those previously filed, until the clip is filled.

The paper-holders or points P are such as are now in common use for binding by opening and reversing their ends. These points P are secured by sliding them over the hook on the lower end of the spring-catch G, and then under the slotted and opened retaining-lugs O on the inner side of the back or head plate A. The spring G, which should be made of steel, has its upper end formed into a hook, which hooks into a perforation, I, in the plate A. Its lower point is also hooked for holding the heel of the paper-holder or point P in its position, so that it may be removed and replaced by others, on emptying the file or clip, for binding or otherwise preserving the file of papers.

I am aware that a file and clip was patented so late as the 4th of January, 1870, which is designed to perform the same functions, but

differs substantially in its construction and operation from mine. I am also aware that coiled springs, in connection with a press-plate, are not new, but differ substantially in the arrangement. I therefore do not broadly claim the springs.

What I claim as my invention, and desire to secure by Letters Patent, is—

1. The drawing-key B with its hinged prop-casing C, in combination with the sliding press-plate D, guide-bolts L, and springs K, all ar-

ranged and operating substantially in the manner and for the purpose specified.

2. In combination with the plate A and its perforations I, the hook-spring G and the slotted open lug O for holding the heel of the paper-points P, substantially in the manner and for the purpose set forth.

THOMAS C. FAHNESTOCK.
